UNITED STATES PATENT OFFICE.

CHARLES C. LANE, OF LOS ANGELES, CALIFORNIA.

ORE-CRUSHING MACHINE.

SPECIFICATION forming part of Letters Patent No. 623,088, dated April 11, 1899.

Application filed May 11, 1898. Serial No. 680,383. (No model.)

To all whom it may concern:

Be it known that I, CHARLES C. LANE, a citizen of the United States, residing at Los Angeles, in the county of Los Angeles, State of California, have invented a new and useful Improvement in Ore-Crushing Machines, of which the following is a specification.

My invention relates to improvements in that class of ore-crushing machines in which crushing-rolls are caused to travel upon annular dies situate in the bottom of an annular pan.

The object of my invention is to provide an ore-crushing machine of small dimensions at little expense that can be easily operated with a small amount of power, it being adapted as to size and mechanical construction with a view to the use of animals as a motor power and its location in inaccessible places where large and heavy machinery could not be located with profit or at all.

My invention consists in the novel means of operating the crusher by affixing to the frame journals in which the axles of the crushing-rolls are mounted, so that the rotation of the frame will cause the rolls to move, and thereby operate the crusher, also the novel means of regulating the pressure of the crushing-rolls and the formation of the same, in providing suitable channels at the sides of the dies for the amalgam, in providing a revolving continuous feed, and in other features herein described and claimed.

I attain these objects by means of the mechanism described herein and illustrated in the accompanying drawings, in which—

Figure 1 is a central vertical section of the machine. Fig. 2 is a plan view of one of the crushing-rolls with its axle and showing the mechanism for its adjustment and also a lever or arm attached for the use of animal power.

A is a circular pan, on the bottom of which are annular dies B. These dies are preferably made of steel in the form of rings like wagon-tires and placed one over the other, making a compact whole. They may be made in sections or, if preferred, cast in one solid piece. I prefer them made as shown, as they are more easily handled and replaced when worn out. The bottom C of the pan is made of wood of suitable thickness, securely fastened

to the usual bed-timbers. (Not shown in the drawings.) The rim A' of the pan is preferably made from sheet-iron. Inside of the rim and resting on the bottom C is an annular ring of wood D, having a sloping top, on which is placed a strip of rubber packing L, having a flange extending up alongside the rim. On this ring of packing is placed a ring M of sheet-copper. Resting on the bottom C, adjacent to the ring D, is an annular ring g of iron. Between the ring g and the dies B is a securely-wedged ring of wood f, the top of which is lower than the top of the dies. 65 On the inner side of the dies is wedged a similar wooden ring e, and adjacent thereto is an annular ring of iron d. Adjacent to the ring d and securely fastened to the bottom C is a circular ring b, preferably made of sheet-iron. 70 The ring b and the rim A' form the sides of a trough X' for holding the material to be crushed, the bottom of the trough being formed of the dies and wooden rings e and f. The tops of the rings e and f, being lower than 75 the dies and adjacent rings, form channels Y for the reception of quicksilver. At a suitable point in this circular trough the rim A', rings D M, and packing L are cut away to a level with the top of the ring g to form the 80 usual sluice-gate, which is provided with the usual screen. (Not shown in the drawings.)

Slidably mounted on the central stationary vertical shaft E is a plate F, having slots F' for mounting thereon journal-box H, which 85 forms a bearing for the inner end of axle I. These slots in the plate F permit the adjustment of the inner end of the axle I, so that it is radial or non-radial to the path of revolution of the rolls O. The purpose of this adjustment is to give greater or less grinding motion to the rolls O in their passage over the dies. The opening in the journal-box H is large enough to permit the axle I to have the necessary vertical movement. On the outer 95 end of the axle I are mounted the crushing-rolls O. These rolls may be constructed of any suitable material. I prefer to construct them in two parts, the central part O' of wood and the tire O² of steel. The axle I also passes 100 through a journal-box N, (shown in section in Fig. 2,) slidably mounted in the frame P between the standards P⁴. The journal-box N is partly convex on its outer sides to permit

of the axle being shifted at its inner end, as shown in Fig. 2. The frame P is preferably constructed of angle-iron. It consists of the annular ring P' at the bottom, annular ring P², securely bolted to a strong wood top P³, eight standards P⁴, one on each side of the axle, forming a support for the axle-journal N. These standards are braced by brace-rods P⁵. The inner surfaces of the standards P⁴ are slightly concave on their inner faces, providing thereby a movable fit for the journal-box N, as shown in Fig. 2. Securely fastened around the circumference of the top P³ is a metal ring P⁶, forming a drum or pulley for a driving-belt, (not shown,) whereby the frame P, carrying the rolls O, may be rotated. Over the journal-boxes N and between the upright standards P⁴ are mounted strong spiral springs T to give a yielding pressure to the axle of the rolls O as the rolls pass over unequal thicknesses of ore on the dies B. The tension of the springs T is regulated by means of the screws V, which pass through the threaded followers V', slidably mounted in standards P⁴. As the followers V' do not rotate when the screw V is rotated, it forces the follower V' down upon spring T, which thereby presses on journal-box N, and thus enables a different pressure to be put on each crushing-roll. On the top of the frame is the feed-hopper J, fastened thereto by standards J'. The hopper J has a shaking bottom J², which is attached to the hopper by chains J³. Attached to the bottom J² is an iron lug J⁴, adapted to strike against the pin K', and thereby impart to the bottom J² a shaking motion on each revolution of the frame. Should one pin be insufficient to give the bottom the shaking required more can be added. Leading from the feed-hopper J to the trough in front of one of the rolls O is a chute W, affixed to and carried by the frame P and adapted to discharge the ore directly in front of one of the rolls upon the dies B. On the stationary shaft E, near its top, is placed a nut h' to securely fasten the bottom C and frame P together. Between the nut h' and the top P³ of the frame are mounted ball-bearings R. The stationary vertical shaft E passes through the bottom C of pan A and through the wood top P³ of the frame and has nuts h and h' screwed thereon to keep the parts from separating when ore is being crushed. Quicksilver is put in the channels on each side of the dies. Water is run into the pan opposite the flush-gate. (Not shown in the drawings.) The frame carrying the crushing-rolls is caused to rotate. Ore is fed into the hopper and is carried through the chute and discharged upon the dies in front of one of the rolls, thereby giving an even feed of ore along the whole face of the dies. As the ore is crushed the gold separates from the rock and is caught by the quicksilver in the chan-

nels. It will be observed that by my form of construction the dies can be worn first on one face and then changed to the other, thereby obtaining more wear out of them than if they could not be turned; also, that when worn out they can be replaced without injury to the other parts of the machine; also, that by making the crushing-rolls with a steel tire the tire can be replaced by a new one when worn out. It will be further observed that as the bottom of the pan carrying the dies is connected with the frame carrying the crushing-rolls any desired pressure can be put upon the crushing-rolls by means of the screws by which they are adjusted, and that as each roll has a separate adjustment it may have a different crushing power on the ore from the others.

I have shown a machine having four crushing-rolls; but a machine having two or more rolls would work as well. If desired, the copper plate M, packing L, and the wood ring D can be omitted. By making the rim A' and inner ring b strong enough the rings of iron d and g could be dispensed with. Their principal use is to give strength, and thereby enable the rim A' and ring b to be made of light material. In Fig. 2 I have shown an arm X projecting out from the plate F, to which the inner end is affixed at Z', then over the annular ring P', on which the outer bearing Z of the arm is attached. This arm is provided with whiffletrees, (not shown,) to which an animal may be hitched, providing means to operate the crusher with animal power, this being essential to a crusher of the size of mine, where steam or other power is not obtainable.

Having thus described my invention, what I claim as new, and desire to secure by Letters Patent, is—

In an ore-crusher the combination of the circular pan A; dies B resting on the bottom of pan A; the central vertical shaft E; the removable circular plate F formed with slots F' movably mounted on the shaft E; ring P'; standards P⁴ mounted on ring P'; actuating-drum P⁶; swiveled journal-boxes N movably mounted in standards P⁴; spring T mounted between standards P⁴ over journal-boxes N; screws V with threaded screw-followers V', the followers slidably mounted in standards P⁴ over springs T; shafts I mounted in journal-boxes N and having the bearings for their inner ends laterally adjustable in the slots F' and the edge-runners or crushing-rolls O mounted upon shaft I, substantially as described.

Signed by me, at Los Angeles, California, this 27th day of April, 1898.

CHARLES C. LANE.
